[57] CLAIM

The ornamental design for an anti large bird feeding perch, substantially as shown and described.

DESCRIPTION

FIG. 1 is a front perspective view of an anti large bird feeding perch showing my new design;

FIG. 2 is a right side elevational view thereof;

FIG. 3 is a left side elevational view thereof;

FIG. 4 is a rear elevational view thereof;

FIG. 5 is a bottom plan view;

FIG. 6 is a top plan view thereof;

FIG. 7 is a front perspective view of a modified form of the anti large bird feeding perch shown in FIG. 1;

FIG. 8 is a front elevational view of FIG. 7;

FIG. 9 is a bottom plan view of FIG. 7; and

FIG. 10 is a top plan view of FIG. 7.

FIG. 1

FIG. 2

FIG. 3

FIG. 4

FIG. 5

FIG. 6

FIG. 7

FIG. 8

FIG. 9

FIG. 10
